COLLAR ATTACHING MEANS

Rae N. Heldenbrand, San Diego, Calif.

Application September 17, 1936, Serial No. 101,303

3 Claims. (Cl. 2—139)

The present invention relates to new and useful improvements in shirts and has for its primary object to provide, in a manner as herein-after set forth, an article of apparel of this character embodying novel means for detachably securing a removable collar thereto.

Another very important object of the invention is to provide a shirt of the aforementioned character embodying means for securing a detachable collar thereto without the use of the usual buttons and button holes.

Still another very important object of the invention is to provide a means for attaching shirt collars which will be invisible and wherein the securing elements will not contact with the skin of the wearer.

Other objects of the invention are to provide a collar attaching means of the aforementioned character for shirts which will be comparatively simple in construction, strong, durable, highly efficient and reliable in use, comfortable and which may be manufactured at low cost.

All of the foregoing and still further objects and advantages of the invention will become apparent from a study of the following specification, taken in connection with the accompanying drawings wherein like characters of reference designate corresponding parts throughout the several views and wherein:

Figure 1 is a view in front elevation of the upper portion of a shirt and collar equipped with the present invention.

Figure 2 is a view in front elevation of the upper portion of the shirt with the collar omitted.

Figure 3 is a view in horizontal section, taken substantially on the line 3—3 of Figure 2.

Figure 4 is a view in rear elevation of the upper portion of the shirt.

Figure 5 is an elevational view of the collar, showing same in its flat form and looking at the inner side thereof.

Figure 6 is a view in horizontal section through one end portion of the collar taken substantially on the line 6—6 of Figure 5.

Figure 7 is a view in horizontal section through the other end portion of the collar, taken substantially on the line 7—7 of Figure 5.

Figure 8 is a detail view in perspective of the front securing bar.

Figure 9 is a detail view in perspective of the rear securing bar.

Referring now to the drawings in detail, it will be seen that the reference numeral 1 designates the upper portion of a shirt which is pro-

vided with a neck band 2. The free lower edge of the outer fold of the neck band 2 is stitched, as at 3. An opening 4 (see Figure 4) is provided in the outer fold of the neck band 2 at the rear thereof for a purpose which will be presently set forth. The inner fold of the neck band 2 is designated by the reference numeral 5 and the outer fold thereof by the reference numeral 6.

As illustrated to advantage in Figures 2 and 3 of the drawings, one end portion of the neck band 2 has formed therein a vertically elongated opening 7. On the other end portion of the neck band 2 the outer fold 6 thereof is provided with spaced slits providing a vertical loop 8 which is adapted to be projected forwardly through the opening 7. The reference numeral 9 designates a bar of suitable resilient metal which is adapted to be inserted through the loop 8 after said loop is projected through the opening 7 for releasably securing the neck band 2 closed. The front securing part 9 comprises a forwardly offset end portion 10 providing a shoulder 11.

The reference numeral 12 designates generally a detachable collar comprising inner and outer folds 13 and 14, respectively. The inner fold 13 is provided, at the back of the collar 12, with spaced, vertical slits 15 providing a loop 16 through which a back securing bar 17 of suitable resilient metal is adapted to be inserted. The end portions of the back securing bar 17 are engageable in the outer fold 6 of the neck band 2 through the opening 4 for detachably securing the back of the collar to the shirt.

On one end portion, the inner fold 13 of the collar 12 is provided with a pocket 17' for the reception of one end of the front securing bar 9. Adjacent the mouth of the pocket 17' the inner fold 13 of the collar 12 is further provided with an opening 18. The opening 18 is to permit the forwardly offset end portion 10 of the front securing bar 9 to be inserted through the inner fold 13 of the collar 12 from the inner side to the outer side of said inner fold. It will be observed that the pocket 17' is on the inner side of the inner fold 13 of the collar. The flexibility of the front securing bar 9 will permit the end portion 10 of said securing bar to be inserted through the opening 18 after the other end of said securing bar has been engaged in the pocket 17'.

The reference numeral 19 designates a pocket on the inner fold 13 of the collar 12 at the other end of said collar. The pocket 19 is for

the reception of the forwardly offset end portion 10 of the front securing bar 9.

It is thought that the manner of securing the collar to the shirt will be readily apparent from a consideration of the foregoing. The resilient back securing bar 17 is first mounted in the loop 16 and the projecting end portions thereof are then inserted or engaged beneath the outer fold 6 of the neck band 2 through the opening 4, thereby firmly but detachably securing the collar to the back of said neck band. Adjacent the opposite sides of the opening 4, the outer fold 6 of the neck band 2 is secured by vertical rows of stitches 21 for retaining the bar 17 against longitudinal movement. The end portions of the neck band 2 are then brought together in overlapping relation (see Figure 3) and the loop 8 is drawn forwardly through the opening 7, after which the front securing bar 9 is inserted through said loop 8. The shoulder or abutment 11 functions to retain the front securing bar 9 in position against longitudinal movement and compensates for the thickness of the inner portion of the collar 13. The end portion of the collar 12 which carries the pocket 17' is then brought around the neck and the offset end portion 10 of the front securing bar 9 is inserted through the opening 18. The other end portion of the front securing bar 9 is then engaged in the pocket 17', thus securing this end of the collar. The other end of the collar 12 is then brought around the neck and the end portion 10 of the securing bar 9 is engaged in the pocket 19. The operation of attaching the collar has thus been completed. It will be noted that the securing elements 9 and 17 are provided with rounded ends and that the pockets 17' and 19 are correspondingly shaped. The reference numeral 20 designates the usual wings with which the collar 12 may be provided.

It is believed that the many advantages of a shirt collar attaching means constructed in accordance with the present invention will be readily understood and although a preferred embodiment of the invention is as illustrated and described, it is to be understood that changes in the details of construction and in the combina-

tion and arrangement of parts may be resorted to which will fall within the scope of the invention as claimed.

What is claimed is:—

1. The combination with a shirt comprising a neck band having an opening in one end portion thereof and a flexible loop on its other end portion adapted to be inserted through the opening, of a securing bar adapted to be inserted through the loop for securing the ends of the neck band together, and a collar, said collar comprising a pocket on one end for the reception of one end of the securing bar, said collar having an opening in said one end portion thereof adjacent the pocket for the passage of the other end portion of the securing bar, and a pocket on the other end of the collar for the reception of said other end portion of the securing bar. 5 10 15

2. The combination with a shirt comprising a neck band having an opening in one end portion thereof and a flexible loop on its other end portion adapted to be inserted through the opening, of a securing bar adapted to be inserted through the loop for securing the ends of the neck band together, and a collar, said collar comprising a pocket on one end for the reception of one end of the securing bar, said collar having an opening in said one end portion thereof adjacent the pocket for the passage of the other end portion of the securing bar, and a pocket on the other end of the collar for the reception of said other end portion of the securing bar. 20 25 30 35

3. The combination with a shirt including a neck band having an opening in one end portion thereof and including a flexible loop on its other end portion adapted to be inserted through the opening, of a securing bar adapted to be inserted through the loop, and a collar comprising pockets on its end portions for the reception of the ends of the securing bar, said collar having an opening in one end portion for the passage of one end portion of said securing bar. 40 45
